ATTORNEY.

UNITED STATES PATENT OFFICE.

ARTHUR B. KENDRICK, OF EAST ORANGE, NEW JERSEY.

JOCK-STRAP.

1,092,488.

Specification of Letters Patent.

Patented Apr. 7, 1914.

Application filed May 10, 1913. Serial No. 766,691.

To all whom it may concern:

Be it known that I, ARTHUR B. KENDRICK, a citizen of the United States, residing at East Orange, in the county of Essex and 5 State of New Jersey, have invented certain new and useful Improvements in Jock-Straps, of which the following is a specification.

This invention relates to jock straps comprising a waist band and a supporting member attached thereto.

The object of the invention is to provide a supporting member of novel, simple and efficient construction, formed entirely of two 15 strips of fabric having their ends attached to the waist band and folded and stitched together to form a supporting pouch having parts reinforced by being formed of double thicknesses of the fabric.

20 A further object of the invention is to construct the said supporting member of strips of knitted fabric, more elastic transversely than longitudinally, and associating the parts of the strips in a manner to provide a pouch which will adjust itself to the wearer when in use.

The precise nature of the invention will be hereinafter fully described and claimed.

In the accompanying drawings, illustrating my invention: Figure 1, is a side view of a jock strap embodying my invention. Fig. 2, is a front view thereof. Fig. 3, is a plan thereof. Fig. 4, is a front view of a portion of the two strips of fabric, showing one position thereof while being folded and formed into the pouch, the general form of the knitted stitch forming the strips being indicated on the strips at the top of the figure. Fig. 5, is a top view of the two strips 40 of fabric. Fig. 6, is a view of the parts shown in Fig. 4 after the parts have been finally adjusted and stitched to form the pouch.

Referring to the drawings, 2 designates 45 the waist band which, in the present embodiment of my invention is a plain endless band formed of suitable elastic material adapted to be stretched around the waist of the wearer and to be held in place by the 50 elasticity of the band.

The supporting member 3 depending from the waist band 2 is formed of two strips of fabric 4 which are folded and stitched together and to the band 2, as will 55 be hereinafter explained. Each strip 4 preferably comprises a flattened, knitted

tube such as is commonly employed in knitted neckties and the leg portions of seamless stockings. Such flattened knitted tubes are much more elastic transversely or in the 60 direction of the width thereof than longitudinally or in the direction of the length thereof and this is particularly true of the well known ribbed knitted tubes. I may employ either the plain or the ribbed knitted 65 tubes in carrying out my invention.

In forming the supporting member 3, I place the edges of the two strips 4, at one end thereof, together and unite the edges by a line of stitching 5 from one end of the 70 pair of strips 4 to the point 6, shown in Fig. 4. I then fold the strips 4 on diagonal lines 7, Fig. 4, so that the strips will extend away from each other and at right angles to the line of stitching 5, each strip forming a triangular portion 8 of double thickness of the strip of fabric, and each triangular portion 8 forming one-half of a square. I then stitch the two edges of the strips forming the sides 9 and 10 of the triangles 8 to the 80 bodies of the strips 4. This being done I bring the fold lines 7 together and unite them by stitching 11, as shown in Fig. 6. The bringing together of the triangular portions 8 forms a square outlined by the four 85 straight lines of stitching 9, 9 and 10, 10, as shown in Fig. 6, where the square appears distorted owing to the bringing together, at the point 12, of the outside edges of the vertical portions of the strips 4. By 90 thus bringing together these outside edges at the point 12, I form a pouch or pocket 13, the lower or base portion of which is formed by the square above mentioned, and the sides of which are formed by the strips 95 4 extending upwardly from the lines of stitching or sides 9 of the said square portion.

The ends 14 of the forward portions of the strips 4 are expanded or spread and 100 stitched to the forward portion of the waist band 2, as clearly shown in Fig. 2; and the portions 15 of the strips 4 extending from the lines of stitching 10 are brought up to the sides of the waist band 2 and stitched 105 thereto, as clearly shown in Figs. 1 and 2.

When applying the jock strap to the wearer, the legs are passed through the waist band 2 and openings 16, and the waist band is drawn up and adjusted about the 110 wearer's waist as the pouch or pocket 13 receives the parts to be supported.

The four lines of stitching 9, 9 and 10, 10 inclosing the square which forms the bottom or base of the pouch or pocket 13, unite four longitudinal edge portions of the strips 4 to the body portions thereof, on lines extending transversely of the strips, thereby reducing the stretchability of the four lines 9, 9 and 10, 10 to a large extent while permitting the relatively free stretching of the fabric within the lines 9, 9 and 10, 10 toward the center of the square inclosed thereby. This construction permits the square forming the bottom portion or base of the pouch or pocket 13 to readily conform to the parts supported therein, resulting in ease and comfort to the wearer.

By expanding the upper ends 14 of the front portions of the strips, it will be observed that the sides of the pouch or pocket 13 are drawn upwardly, thereby enhancing the pouch or pocket effect produced by folding and stitching the strips 4 as hereinbefore described.

I claim:

25 1. In a jock strap, a waist band, and a supporting member formed of two flat continuous strips of fabric having their ends attached to the waist band, each of said strips being folded upon itself forming a triangular portion of double thickness of the fabric, said triangular portions being stitched together, said strips extending upwardly from the triangular portions to the front of the waist band and said strips diverging from the triangular portions and extending to the sides of the waist band.

2. In a jock strap, a waist band, and a supporting member formed of two flat strips of fabric having their ends attached to the waist band, each of said strips being folded upon itself forming a triangular portion of double thickness of the fabric and equal substantially to one-half of a square, said triangular portions being stitched together forming a substantially square portion of double thickness of the fabric, portions of said strips being stitched together forming a pouch including said square portion, said strips extending forwardly from the square portion to the front of the waist band, and said strips diverging from the square portion and extending to the sides of the waist band.

55 3. In a jock strap, a waist band, and a supporting member formed of two flat strips of fabric having their ends attached to the waist band, each of said strips being folded upon itself forming a triangular portion of double thickness of the fabric and equal substantially to one-half of a square, the folded sides of said triangular portion being stitched together forming a substantially square portion of double thickness of the fabric, the parts of said strips forming the square portion being stitched together

around the outer portion of the square portion, said strips extending upwardly from the square portion to the front of the waist band, said strips being stitched together above the square portion, forming a supporting pouch including said square portion, and said strips diverging from the square portion and extending to the sides of the waist band.

4. In a jock strap, a waist band, and a supporting member formed of two flat strips of fabric having their ends attached to the waist band, each of said strips comprising a flattened knitted tube more elastic in the direction of its width than in the direction of its length, each of said strips being folded upon itself forming a triangular portion of double thickness of the fabric and equal substantially to one-half of a square, said triangular portions being stitched together forming a substantially square portion of double thickness of the fabric, portions of said strips being stitched together forming a pouch including said square portion, said strips extending upwardly from the square portion to the front of the waist band, and said strips diverging from the square portion and extending to the sides of the waist band.

5. In a jock strap, a waist band, and a supporting member formed of two flat strips of fabric having their ends attached to the waist band, each of said strips comprising a flattened knitted tube more elastic in the direction of its width than in the direction of its length, each of said strips being folded upon itself forming a triangular portion of double thickness of the fabric and equal substantially to one-half of a square, the folded sides of said triangular portion being stitched together forming a substantially square portion of double thickness of the fabric, the parts of said strips forming the square portion being stitched together around the outer portion of the square portion, said strips extending upwardly from the square portion to the front of the waist band, said strips being stitched together above the square portion, forming a supporting pouch including said square portion, and said strips diverging from the square portion and extending to the sides of the waist band.

6. In a jock strap, a waist band, and a supporting member formed of two flat strips of fabric having their ends attached to the waist band, each of said strips comprising a flattened knitted tube more elastic in the direction of its width than in the direction of its length, said strips being folded and stitched together forming a supporting pouch, said strips extending upwardly from the folded portions to the front of the waist band, said strips diverging from the folded portions and extending to the sides of the

waist band, and the ends of the forward portions of the strips being expanded and held in expanded condition by being attached to the waist band.

- 5 7. In a jock strap, a waist band, and a supporting member formed of two flat strips of fabric having their ends attached to the waist band, each of said strips comprising a flattened knitted tube more elastic
10 in the direction of its width than in the direction of its length, each of said strips being folded upon itself forming a triangular portion of double thickness of the fabric and equal substantially to one-half of a square,
15 the folded sides of said triangular portion being stitched together forming a substantially square portion of double thickness of

the fabric, the parts of said strips forming the square portion being stitched together around the outer portion of the square portion, said strips extending upwardly from the square portion to the front of the waist band, said strips diverging from the square portion and extending to the sides of the waist band, and the ends of the forward portions of the strips being expanded and held in expanded condition by being attached to the waist band. 20
